UNITED STATES PATENT OFFICE

147,762

DESIGN FOR A PIN OR SIMILAR ARTICLE

Oreste Pennino, Jamaica, N. Y.

Application July 18, 1946, Serial No. 131,678

Term of patent 3½ years

(Cl. D45—19)

To all whom it may concern:

Be it known that I, Oreste Pennino, a citizen of the United States, residing at Jamaica, in the county of Queens and State of New York, have invented a new, original, and ornamental Design for a Pin or Similar Article, of which the following is a specification, reference being had to the accompanying drawing, forming part thereof.

In the drawing:

Fig. 1 is a front view of a pin showing my new design;

Fig. 2 is a rear view thereof; and
Fig. 3 is a side view thereof.

I claim:

The ornamental design for a pin or similar article, as shown.

ORESTE PENNINO.
